FAUCET

Alan R. Cripe, Chagrin Falls, Ohio, assignor to Tomlinson Industries, Inc., Cleveland, Ohio, a corporation of Ohio

Filed Dec. 14, 1959, Ser. No. 58,654

Term of patent 14 years

(Cl. D2—3)

FIG. 2

FIG. 3

FIG. 4

FIG. 5

Fig. 1 is a perspective view of a faucet, showing my new design;

Fig. 2 is a front elevation thereof;

Fig. 3 is a side elevation thereof;

Fig. 4 is a top plan view; and

Fig. 5 is a cross-sectional view taken along line 5—5 of Fig. 2.

The essential features of the design are shown in solid lines.

I claim:

The ornamental design for a faucet, as shown and described.
